Primary Examiner — Leah Macchiarolo*Assistant Examiner* — Christina Gabrielle Cosden(74) *Attorney, Agent, or Firm* — AdamsIP, LLC; Earl Walter Reed, III; James Hunter Adams(57) **CLAIM**

The ornamental design for a container latch, as shown and described.

DESCRIPTION

FIG. 1 is a top front right perspective view of a container latch showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and

FIG. 7 is a bottom view thereof; and,

FIG. 8 is a top right perspective view of the container latch showing the claimed design in an environment in which it may be used.

The dashed broken lines in the figures show portions of the container latch subject matter that form no part of the claimed design.
